CLAIM

The ornamental design for an ultrasonic transducer probe, as shown and described.

DESCRIPTION

FIG. 1 is a perspective view of an ultrasonic transducer probe showing my new design;

FIG. 2 is a left side elevational view thereof;

FIG. 3 is a right side elevational view thereof;

FIG. 4 is a top plan view thereof;

FIG. 5 is a front elevational view thereof;

FIG. 6 is a rear elevational view thereof; and,

FIG. 7 is a bottom plan view thereof.

The fragmented showing of a cable in FIGS. 1, 2, 3, 4, 6, and 7 is for convenience of illustration.

FIG-1

FIG-2

FIG-3

FIG-4

FIG-5

FIG-6

FIG-7
